ERNEST H. SHAFF, OF GRAND HAVEN, MICHIGAN, ASSIGNOR TO WILLIAM H. KELLER, INC., OF GRAND HAVEN, MICHIGAN, A CORPORATION OF MICHIGAN.

FLUID-PRESSURE-OPERATED TOOL.

Application filed April 5, 1920. Serial No. 371,444.

To all whom it may concern:

Be it known that I, ERNEST H. SHAFF, a citizen of the United States, residing at Grand Haven, in the county of Ottawa and State of Michigan, have invented certain new and useful Improvements in Fluid-Pressure-Operated Tools, of which the following is a specification.

This invention relates to fluid-pressure-actuated tools, and refers more particularly, though not essentially, to tools of the percussion type commonly known as pneumatic hammers.

The general object of the invention is to produce a tool of novel construction which includes means for separating and storing a portion of the working charge of motive fluid which moves the piston on its power stroke, and for utilizing such separated or stored portion to move the piston on its opposite or return stroke.

More specifically, the invention aims to provide means including a piston chamber, a storage chamber, and a valve device arranged to automatically open to allow the escape of a portion of the charge of the working fluid from the piston chamber into the storage chamber and to close to prevent the return of the stored motive fluid through the valve, the tool being constructed to cause the stored portion to re-enter the piston chamber at the opposite side of the piston for returning the latter.

In the accompanying drawings Figure 1 is a longitudinal sectional view through a pneumatic hammer which is constructed in accordance with my invention. Fig. 2 is an enlarged sectional view of the rear portion of the tool taken on the same plane as Fig. 1, but showing the main control valve in another position. Fig. 3 is a fragmentary sectional view on an enlarged scale illustrating the valve for the admission of motive fluid into the storage chamber. Fig. 4 is a perspective view of the latter valve. Fig. 5 is a fragmental sectional view of the forward portion of the tool, showing an alternative construction. Fig. 6 is a transverse section on line 6-6 of Fig. 5.

My invention is herein shown as applied to a pneumatic hammer and will be described in detail for the sake of clearness, but it should be understood that I do not

intend to limit the invention to the present exemplary disclosure, but aim to cover in 55 the appended claims all modifications and equivalents falling within the scope of my invention.

The tool shown in the drawings comprises a body or cylinder 10 having an internal 60 piston chamber in which a solid piston 11 reciprocates. In the forward end of the cylinder is fitted the usual rivet set or analogous working tool 12 against which the piston strikes at the end of its working 65 stroke.

At the rear end of the cylinder is the usual handle 13 having a tubular head 14 which may be mounted on the body in any preferred manner, as by means of screw 70 threads, the handle being locked to the cylinder to prevent rotation of the handle by any suitable means 15, which need not be described in detail. The handle has a supply passage 16 for live motive fluid, which 75 passage is controlled by a manually operated throttle valve, the lever of which is designated 17.

The storage chamber hereinbefore referred to for receiving and storing a portion of the working charge of motive fluid may be provided in a number of different ways. The preferred means which is herein shown comprises an inner tube 18 which is of smaller external diameter than the interior of the cylinder 10 thereby providing an annular space 19 between the tube and cylinder. The front end of the tube 18 fits snugly within a bore in the interior of the cylinder 10, and the rear end of the 80 tube has an annular flange 18^a which is received within a counterbore in the rear end of the cylinder and is arranged to abut against a shoulder provided by such counterbore.

Fitting within the bore at the rear end of the cylinder partially enclosed by the head 14 of the handle is a tubular valve casing 20 which in the present instance is made of two interfitting sections. When the handle 100 is turned up on its threads the valve sections and the flange 18 of the inner tube are securely clamped in place.

A tubular valve member 21 fits slidably within the valve casing and has a plurality 105 of external annular flanges thereon form-

ing shoulders against which the pressure of the motive fluid is exerted to move the valve member in opposite directions.

The handle head 14 provides an annular chamber 22 surrounding the rear end of the valve casing 20 and in constant communication with the supply passage 16 for the live motive fluid.

The rear end of the valve casing 20 is provided with inlet means 23, which may comprise an annular series of ports communicating with an internal annular groove in the valve casing, through which inlet means live motive fluid is introduced into the rear end 15 of the piston chamber to move the piston on its forward or power stroke when the valve member 21 is in its forward position as shown in Fig. 2.

The valve 21 is held in its forward position by live air pressure in a rear valve chamber 24 acting upon the rear flange 25 on the valve member, the said chamber being in constant communication with the supply of live motive fluid through a small 25 port 26.

The extreme forward end of the storage chamber 19 is in constant communication with the extreme forward end of the piston chamber through suitable means such as 30 grooves 27 cut in the forward end of the inner tube 18. The rear end of the storage chamber is in constant communication with a valve chamber 28 through a suitable number of ports or passages 29. The forward 35 flange 30 on the valve member 21 moves in the valve chamber 28 and is governed by the pressure in said chamber to shift the valve rearwardly as will be later explained.

When the valve member is in its forward 40 position the valve provides a restricted passage connecting the chamber 28 with another chamber 31 in the valve casing and the latter chamber 31 is in constant communication with the atmosphere through a suitable 45 number of exhaust passages 32 leading therefrom to the exterior surface of the cylinder 10. By the means described the spent charge of motive fluid in the forward portion of the piston chamber is permitted 50 to exhaust through the storage chamber and thence to the atmosphere while the piston is traveling forward.

A passage 33 connects the rear portion of the front valve chamber 28 with one of the exhaust passages 32. Another passage 55 34 connects the rear portion of the rear valve chamber 24 with the piston chamber at a point forward of the valve 21. The purposes of these two last described passages 60 will be explained later.

The means for introducing a portion of the live charge of motive fluid into the storage chamber 19 and for preventing the return of such fluid behind the piston comprises in the preferred form herein shown 65

an annular series of ports 35 through the wall of the inner tube 18, and means normally closing said ports and arranged to be operated by the pressure of the motive fluid in the piston chamber to open the ports 70 and allow the escape of the motive fluid from the piston chamber into the storage chamber.

I have shown in the drawings two alternative constructions of means for closing 75 the ports 35. Referring first to Figs. 1, 3 and 4, the said means is in the form of an annular resilient valve member 36 which fits in an external annular groove 37 in the tube, the ports 35 at their outer ends opening 80 into said groove. In order to avoid unduly weakening the tube the latter is provided with an annular external enlargement, the groove 37 being cut in this enlargement and providing two annular ribs 38 on the tube. Preferably also the ports 35 are drilled at an angle other than a right angle to the axis of the tube for the sake of strength. 85

The valve member 36 is of beveled formation and the bottom of the groove 37 is tapered or inclined, so that when the motive fluid within the piston chamber forces the valve member to expand it will also force a movement of the valve member lengthwise of the tube along the tapered bottom 90 of the groove. The outer edge of the valve member is therefore moved into contact with the inner surface of the cylinder 10 as indicated by dotted lines in Fig. 3. When the pressure in the piston chamber is relieved 95 the inherent resiliency of the valve member causes it to contract and the tapered bottom wall of the groove forces the valve member to move axially of the tube into contact with the upper edge of the groove so as to 100 close all the ports 35. 105

Referring now to the alternative construction shown in Figs. 5 and 6, the valve means is in the form of separate leaf springs 40 extending longitudinally of the tube 18 and are suitably secured to one end of the tube by suitable means such as pins or rivets 41. The opposite end of each spring overlies and normally closes one of the ports 35, the surface of the tube 18 being flattened so that the springs fit the tube snugly. The base or attached end of each spring is considerably wider than the free end so that when the tube 18 with the attached springs thereon is inserted into the cylinder the side edges of the widened portions of the spring will be bent inwardly 110 to give a curved shape to the base of the spring. In this manner the springs are held 115 against vibration and are stiffened so that the free ends of the springs will fit snugly against the tube to effectively close the ports 35. 120

In action the springs yield outwardly to 125 the pressure within the piston chamber and 130

return to their port-closing position when the pressures in the storage and piston chambers are approximately balanced as set forth in connection with the form of valve 5 means first described.

The operation of the tool as shown in Figs. 1 to 4 may be described as follows:

Let it be assumed that the main control valve 21 is in its forward position as shown in Fig. 2, (being so held by the pressure in the rear valve chamber 24), and that the piston is at the rear end of the piston chamber. Live motive fluid passes from the supply chamber 22 through the inlets 23 into the rear end of the piston chamber, and acts to move the piston forwardly. The previous spent charge of motive fluid escapes from the forward end of the piston chamber through the grooves 27 into the storage chamber 19, thence through the passages 29 and through the control valve and the chamber 31 and into the exhaust passages 32, and thence to the atmosphere.

When the rear end of the piston in traveling forwardly uncovers the ports 35 in the inner tube 18 the pressure of the motive fluid will open the annular valve 36 and expand it outwardly into contact with the interior of the cylinder and the motive fluid will then pass into the storage chamber 19 and thence into the valve chamber 28.

Inasmuch as the connection between the valve chamber 28 and the exhaust chamber 31 is a very restricted one, the pressure in the valve chamber will build up since the motive fluid cannot escape as fast it is admitted, and therefore the pressure acting upon the large forward flange 30 of the valve member will move the said valve member rearwardly in opposition to the pressure in the rear valve chamber 24 acting on the much smaller flange 25 on the valve member. The pressure within the piston chamber acting upon the extreme forward edge of the valve member also assists to shift the valve rearwardly and approximately counterbalances the effect of the pressure upon the rear flange and the pressure upon the thin extreme rear end of the valve member.

Inasmuch as the expandible valve member 36 closes off the forward end of the storage chamber 19 the live motive fluid is at first prevented from flowing into the forward end of the piston chamber and is instead directed to the rear end of the chamber to shift the main control valve. The series of ports 35 may be located at any desired point along the tube so as to be uncovered by the piston in time to fill the storage chamber 19 with motive fluid while the piston is finishing its working stroke. Thus the chamber 19 is filled with motive fluid and the valve 21 is opened as the piston 11 strikes the tool 12, thereby avoiding delay in the movement of the piston and recoil

of the whole tool. Also the ports may be located sufficiently far from the front end of the piston chamber to permit of using different length pistons.

When the pressure in the rear end of the piston chamber and in the storage chamber has substantially equalized, the valve 36 will contract by its own resiliency and close the ports 35 whereupon the stored charge of pressure fluid in the storage chamber 19 will flow forwardly through the passages 27 into the extreme forward end of the piston chamber and move the piston on its return stroke.

By this time, the main control valve 21 will have been shifted into its rear position as seen in Fig. 1, thereby exposing the exhaust chamber 31 to the piston chamber and allowing the motive fluid in the rear portion of the piston chamber to escape to the atmosphere, the inlet 23 for live motive fluid having been cut off by the rear end of the main control valve 21.

The motive fluid in the rear valve chamber 24 will also be exhausted into the piston chamber through the passage 34, and thence to the atmosphere. When the piston in its rearward movement closes the forward end of the passage 34, the pressure in the rear valve chamber 24 builds up through its supply port 26 and becomes sufficient to shift the main valve 21 forwardly in opposition to the pressure on the large flange 30 which has now been very much lowered by the utilization of the stored motive fluid in the storage chamber. With the valve member 21 in its forward position, a fresh charge of live motive fluid is introduced into the rear end of the piston chamber, and the cycle of operation just described is repeated.

I claim as my invention:

1. A fluid-pressure-operated tool having, in combination, a cylinder, an inner tube spaced from the interior of the cylinder to provide a storage chamber therebetween, the interior of the tube forming a piston chamber, a piston freely movable in said piston chamber, the extreme forward ends of the piston and storage chambers being in communication, an annular series of ports through said tube at a point rearward of the front end of the piston chamber, a groove in the exterior of said tube communicating with said ports, said groove having a tapered bottom wall, an expandible resilient annular beveled valve member occupying said groove, the inclination of the beveled bottom wall of the groove cooperating with the valve member to hold the latter in position to close all of said ports, said valve member being arranged to be expanded by pressure within said piston chamber and to be moved along said tapered bottom wall of the groove and into contact with the in-

terior of said cylinder whereby to cut off the forward portion of the storage chamber and direct the escaping motive fluid rearwardly, and suitable valve mechanism providing for inlet and exhaust of pressure fluid from said piston chamber.

2. In a fluid-pressure-operated tool, a piston chamber, a separate storage chamber in communication with the forward end of said piston chamber, and means to provide communication between the storage chamber and the piston chamber at a point rearward from said forward end, said means including a valve member movable into a position in the storage chamber to separate said storage chamber into two parts and direct into the rear part the motive fluid escaping into the piston chamber.

3. In a fluid-pressure-operated tool, a piston chamber, a separate storage chamber in communication with the extreme forward end of said piston chamber, a piston in said piston chamber, means to provide communication between said two chambers at a point spaced rearward from their forward ends, and valve means including a valve member controlling the last-named means and movable outwardly under pressure from within the piston chamber to cut off the forward portion of the storage chamber and direct the flow of motive fluid into the rear portion of the storage chamber, said piston being arranged to uncover and permit oper-

ation of said means on the forward or working stroke of said piston.

35

4. A valve for controlling the flow of motive fluid in a fluid-pressure-actuated tool adapted normally to close a port leading from the piston chamber to a storage chamber but yieldable outwardly under the pressure of motive fluid in the piston chamber to permit the escape thereof to the storage chamber and forming a partition therein, said valve being in the form of a ring having an inclined wall positioned forwardly of said port when the valve is in its open position and operating to deflect motive fluid discharging from said port to the rear portion of the storage chamber.

45

5. A valve means for controlling the flow of motive fluid in a fluid-pressure-actuated tool including a valve member normally operating to close a plurality of annularly arranged ports leading from the piston chamber to a storage chamber but yieldable outwardly under the pressure of motive fluid in the piston chamber to permit the escape thereof to the storage chamber, said valve forming when in open position a partition in the storage chamber confining the pressure fluid to the rear portion of the chamber.

55

In testimony whereof, I have hereunto set my hand.

ERNEST H. SHAFF.
